UNITED STATES PATENT OFFICE.

ADOLF HODEL, OF WAHPETON, NORTH DAKOTA.

CHIMNEY CAP.

Application filed August 26, 1921. Serial No. 495,644.

To all whom it may concern:

Be it known that ADOLF HODEL, a citizen of the United States of America, residing at Wahpeton, in the county of Richland and 5 State of North Dakota, has invented new and useful Improvements in Chimney Caps, of which the following is a specification.

The object of the invention is to provide a simple and efficient chimney cap or cowl 10 whereby the downward beating of rain or wind due to counterdrafts are excluded from the chimney flue and whereby side winds tending to cause downdrafts are deflected in such a way as to induce upward drafts by 15 suction and thereby increase the draft efficiency of the chimney; and with these objects in view the invention consists in a construction and combination of parts of which a preferred embodiment is shown in the accompanying drawings, wherein:

Figure 1 is a side view of a chimney cap embodying the invention.

Figure 2 is a vertical sectional view of the same.

25 The cap consists of the cylindrical body portion 10 terminating in a double beveled annular cornice 11 which in turn is surmounted by a conical hood 12 preferably having a flat under surface 13 and of a 30 peripheral extent substantially equal to the cornice 11 the hood being supported from the body portion 10 by the uprights 14.

Obviously the conical form of the hood serves to deflect rain and wind due to counterdrafts or eddies (as when the cap is located adjacent to a wall extending above the plane thereof) to prevent a direct opposition to an updraft in the chimney and tends by the lateral deflection of such counterdraft to induce a suction in the chimney, and hence increase the updraft rather than otherwise.

Similarly lateral drafts or winds striking the peripheral edge of the double beveled 45 cornice are split, the portion coming in contact with the upper deflected surface 11^a passing diagonally across the mouth of the

chimney in an upwardly inclined direction while the portion striking the under beveled surface 11^b is deflected downwardly so as to have no impeding effect upon the updraft. Obviously the upwardly deflecting portion of the air draft traversing the line of the chimney flue will tend to induce a suction which will increase the chimney 55 draft.

It will be noted that the upper and under beveled sides of the cornice are of substantially equal width and have their free edges spaced vertically a distance greater than the width of the sides. It will also be noted that the cap has substantially the same radial extent as the cornice and is disposed above the flue a distance not less than the diameter of the flue. Thus, the plane of the 60 upper beveled side of the cornice intersects the plane of the bottom of the cap at a point without the cross sectional area of the flue. Thus, air currents deflected forwardly by the upper side of the cornice will not be 65 intercepted by the bottom portion of the hood close enough to the body portion 10 to cause any downward draft in said body portion.

Having described the invention, what is claimed as new and useful is:

A chimney cap in combination with a cylindrical flue, a double beveled annular cornice disposed in surrounding relation to the flue at the upper edge of the latter, the upper and under beveled sides of the cornice 80 being substantially equal in width and having their free edges vertically spaced a distance greater than the width of said sides, said cornice and cap having substantially the same radial extent, said cap being disposed above the flue at a distance not less than the diameter of the flue, whereby the plane of the upper bevel of the cornice will intersect the plane of the bottom of the cap at a point without the cross-sectional 85 area of the flue.

In testimony whereof he affixes his signature.

ADOLF HODEL.
